(57) **CLAIM**

The ornamental design for an eye drop dispenser, as shown and described.

DESCRIPTION

FIG. 1 is a front view of an eye drop dispenser embodying my new design, the rear view being a mirror image; FIG. 2 is a left side view thereof, the right side view being a mirror image; FIG. 3 is a top view thereof; FIG. 4 is a bottom view thereof; FIG. 5 is a front view thereof in an alternate position, showing an eye cup of the eye drop dispenser in an inverted deployed position and excluding a cap of the eye cup dispenser; and, FIG. 6 is a top view thereof in an alternate position, with the eye cup of the eye drop dispenser in an inverted deployed position and excluding a cap of the eye cup dispenser. Broken lines are used to illustrate features of the eye drop dispenser which form no part of the claimed design.
